UNITED STATES PATENT OFFICE.

LESLIE E. HOWARD, OF LA GRANGE, ILLINOIS, ASSIGNOR TO SIMONDS MANUFACTURING COMPANY, OF FITCHBURG, MASSACHUSETTS, A CORPORATION OF MASSACHUSETTS.

INGOT-CASTING MACHINE.

No. 922,587.

Specification of Letters Patent.

Patented May 25, 1909.

Application filed March 9, 1908. Serial No. 418,948.

To all whom it may concern:

Be it known that I, LESLIE E. HOWARD, a citizen of the United States, residing at La Grange, in the county of Cook and State of Illinois, have invented certain new and useful Improvements in Ingot-Casting Machines, of which the following is a specification.

One object of this invention is to provide an improved apparatus for preventing the formation of blow-holes and cavities in ingots due to the "separating out" of gases from the steel comprising the ingot during the cooling of the same, and the formation of the defect known as "piping" due to the shrinkage of the metal after the outer sides and bottom of the ingot have set and hardened and while the center is still molten, which condition allows the molten metal from the upper portion of the ingot to feed down and partly replace that drawn toward the sides of the lower portion of the ingot owing to shrinkage and cooling. This "piping" or shrinkage cavity is usually confined to the upper portion of the ingot, but may, and often does, extend nearly or quite therethrough.

A further object of the invention is to refine the steel by breaking up the coarse crystallization caused by the slow undisturbed cooling of the ingot as it is usually allowed to proceed, which latter weakens the envelop of metalloids surrounding the crystals of steel, causing a partial loss of cohesion between the crystals. I have found that once this straining and weakening of the steel has taken place, no subsequent heat or mechanical treatment, such as rolling or forging, will fully restore the steel to the strength of like steel in which the formation of coarse crystals and shrinkage has been prevented.

My invention consists of an improved ingot-casting machine in which the ingots are cast, and which is adapted to compress the ingots during the period in which they are passing from the molten to the solid state, such compressing operation commencing immediately after the ingots are poured, and being relatively very gently at first but increasing in force as the ingots become denser as cooling proceeds, the pressure being graduated so as to prevent molten steel flowing from the upper to the lower portion of the ingot until the ingot has "set" or be-

come solid throughout its mass; and after this has occurred the pressure is further increased, producing an effect on the steel similar to hydraulic forging, and the pressure is continued until the steel has cooled to a 60 thermal point somewhat below its point of recalcenece, and the crystals formed throughout the mass of the steel will not undergo any further change by subsequent cooling. To accomplish these results it is 65 essential that the pressure be applied continuously from the commencement of cooling until the point of recalcenece is reached or passed.

While the invention is adapted to the production of ingots of all sizes and shapes, it is especially well adapted to ingots of small sizes, such as are commonly used in the manufacture of tool steel products.

In the accompanying drawings I have 75 illustrated one practical form in which the principle of the invention may be embodied, in which—

Figure 1 is a top plan view of my improved machine. Fig. 2 is a side elevation of the 80 same. Fig. 3 is a cross-section on the line 3—3 of Fig. 1. Fig. 4 is a cross-section on the line 4—4 of Fig. 1.

Referring to the drawings, 5 indicates the main frame of the machine of a rectangular and generally box-like form with its top and bottom open, which frame may be cast in one piece, but preferably, and as herein shown, is composed of side and end members secured together, as by through-bolts 6, and which contains and supports the casting molds and the principal parts of the operating mechanism thereof.

To the inside of one end (hereinafter referred to as the rear end) of the frame 5 are suitably secured compressing cylinders 7, herein shown as two in number, superimposed, with their longitudinal axes horizontal and parallel to each other, and slidably fitted with rams or plungers 8 and provided with pipe connections 9 by which they are connected to a source of fluid pressure (not shown) through a pipe 10 controlled by a regulating valve 11, through which the pressure admitted to the cylinders can be varied as desired, the exhaust being effected through a valve 11a. At the other inside end of the frame 5 (hereinafter referred to as the mold end) are arranged one or more vertically disposed molds, herein shown as two 110

in number disposed side by side, said molds being formed in part by a heavy vertical block or plate 12 forming the backs of the two molds, said block having a central inward projection 12^a forming the two inner side walls of the molds, and securely fastened to the frame 5 by clamps 13, which clamps are suitably formed on their inner ends to engage recesses drilled in the sides of the block 12 near its top, and are held in place by bolts 14.

15 designates vertically and laterally shiftable outer side plates of the molds constituting their outer side walls, which are loosely supported against dropping through the frame when partially removed by pins 16 integral therewith or secured therein near their upper ends and normally resting at their outer ends on the top edge of the sides 20 of the main frame. The remaining side members of the molds which are the active agents in transmitting the pressure applied to the ingots consist of thick upright plates or bars 17, between the outer sides of which 25 and the inner ends of the plunger 8 is fitted a heavy cross-head 18, the weight of which is carried by a bottom plate 19 (Fig. 3) secured as by bolts 20 to the bottom edges of the two sides of the main frame 5. The forward face 30 of the cross-head 18 abuts directly against the outer surfaces or walls of the mold members 17; and the latter are secured to the cross-head for purposes of effecting the retraction of the mold members by means of 35 bolts 21 tapped into or formed integral with the mold members 17, said bolts passing through vertical slots 22 in the face of the cross-head, and the heads 21^a of said bolts being confined in inner enlargements 22^a of 40 said slots by means of removable keys 23 (Fig. 3). The mold members 17 might, of course, be made integral with the cross-head, but are preferably made detachable, as shown, for the sake of renewal or repairs, 45 when necessary, without involving the expense of a new cross-head. Furthermore, the connection described better facilitates an equalizing of the pressure throughout the full length of the ingot than where the compressing mold-members are made integral 50 or rigid with the cross-head.

The bottoms of the twin mold-chambers are closed by a bottom plate 24 that lies loosely in a movable member 25. This latter is 55 pivotally mounted at 26 on an arm 27 in turn pivoted at 28 in and between depending brackets 29 of the sides of the main frame. The arm 27 is caused to swing approximately 60 90 degrees on the shaft 28 by the action of fluid pressure in a motor cylinder 30 beneath and secured to the main frame acting through piston-rod 31 and a link or pitman 32 pivoted at 33 to the arm 27.

Referring now to the means for applying 65 an elastic and yielding pressure upon the

outer sides of the mold-members 15, with which are included means for effecting the retraction of the mold-members 17 after the compression has been completed, 34 designates upper and lower pairs of rectangular bars 70 slidably fitted in grooves 35 (Fig. 3) formed on the inside surfaces of the two side members of frame 5; and attached to the ends of these bars at the mold end of the machine are spring wedge members 36. The 75 inner or operative inclined faces of these wedge members bear and operate against correspondingly inclined projections or shoes 15^a formed on the outer sides of the mold-members 15. These bars, with their attached wedges, are given a longitudinal movement by the action of fluid pressure on a differential piston 37 in a cylinder 38, attached to the outer rear end of the main frame 5, acting through connections 80 consisting of a piston-rod 39, pin 40, cross-bar 41, pins 42, equalizing bars 43, and pins 44 connecting the ends of the latter with the bars 34.

The sides of the cross-head 18 are provided 90 on each side with upper and lower laterally projecting lugs 45 (Figs. 1 and 3) formed integral therewith and so located that in the rearward or retracting travel of bars 34 the inner ends of the wedges 36 will engage lugs 95 45 and thus retract the cross-head, the mold-members 17, and the rams or plungers 8.

The fluid pressure cylinders 30 and 38 are provided with suitable valve-controlled fluid pressure supply-pipes (not shown) adapted 100 to admit the fluid pressure alternately to opposite sides of the pistons of said cylinders at the proper intervals in the operation of the machine, such controlling devices being old and well known and constituting no part of 105 the present invention. The cylinder 38 is preferably provided with a differential piston as shown, permitting a greater pressure to be obtained for effecting the retracting travel of the wedges, which is desirable in the event 110 that the wedges are inclined to stick.

In the operation of the machine, the compressing mold-members 17 are adjusted to the position shown in Fig. 1. The bottom of the mold is then closed by causing the 115 bottom plate 24 to form a closed joint at the bottom end of the longitudinal mold-members through the agency of motor cylinder 30. This causes a slight lifting of the lateral mold-members 15, insuring a tight 120 joint between the bottom plate and all four sides of the mold. The lateral mold-members 15 are then crowded inwardly of the mold through the agency of the motor cylinder 38, wedges 36, and connections 125 therebetween, insuring tight vertical joints between said lateral mold-members and the members 12 and 17. Molten metal is then poured into the mold-chambers by hand or by a suitable pouring ladle until the molds 130

are filled to within two or three inches of their top. Fluid pressure is then applied to the cylinders 7 through the supply-pipes 9, causing a longitudinal movement of the plungers, cross-head, and compressing mold-members 17 toward the mold end of the machine, and lessening the cross-sectional area and volume of the mold-chambers. The operator watches the exposed top ends of the 10 ingots under treatment and, through the valve 11 or other pressure-regulating means, graduates the fluid pressure acting on the plungers so as to effect a sufficient contraction of the cross-section of the ingots during 15 their change from the molten to the solid state as to cause the gradually decreasing portion of molten metal to remain always approximately even and of uniform height with the solidifying sides of the ingots. As soon 20 as the top ends of the ingots appear solid, the pressure is increased somewhat more rapidly, causing a slight forging or kneading action to take place throughout the mass of the ingots, and this pressure is maintained until the 25 metal has attained a stable state of crystallization. The desired compression of the ingots having been thus effected, the supply and exhaust of fluid pressure to the motor cylinders 30 and 38 are reversed, thus dropping 30 the bottom plate 24; retracting the wedges 36, and releasing the pressure of the lateral mold-members 15, and an instant later retracting the cross-head 18 and the compressive mold-members 17. This entirely frees the compressed ingots and leaves 35 them free to drop through and out of the bottoms of the mold-chambers into the space beneath the machine or into any suitable receptacles therefor. The molds are then 40 again adjusted and prepared for subsequent operations, as above described. In practice several of these machines may be provided, placed side by side alongside of a melting furnace or between two furnaces, or otherwise, 45 as may be most convenient in each instance, with their mold ends all in the same relative positions, and the pouring of the molten metal into the molds is best accomplished by means of a pouring ladle in a manner at present well understood and extensively practiced in connection with the production of 50 crucible steel.

I am aware that the practice of applying pressure both laterally and endwise to a 55 steel ingot during its cooling from a molten to a solid state with the object of eliminating bubbles and "piping" and securing a more solid and uniform texture to the entire ingot is broadly old; but the apparatus hereinabove described and forming the subject-matter of the present invention is designed and believed to effect these desirable results with a high degree of efficiency and with increased simplicity in respect to the handling 60 of the ingot both during and subsequent to

compression. Whether the machine embodies a single mold or a plurality of molds, each ingot is independently treated without any delay resulting from the treatment of the other ingot or ingots simultaneously undergoing compression; and by making at least two sides of the mold retractile, the cooled and compressed ingot can be readily discharged without sticking and delaying the re-use of the mold. Furthermore, the drop-bottom feature enables the compressed ingots to be quickly disposed of through the action of gravity alone without requiring the use of hoisting apparatus to get the ingots out of the molds. These and other advantages of the apparatus will be readily apparent to those skilled in the art, and therefore, without limiting myself to the precise construction shown and described, 75

I claim:

1. In an ingot-casting machine, the combination with a vertically disposed mold having a removable bottom plate adapted to close its lower end, and a laterally movable side member, of means for applying pressure 90 to the latter whereby to effect compression of the ingot in the mold, substantially as described.

2. In an ingot-casting machine, a mold substantially rectangular in cross-section 95 and having two of its adjacent sides movable, in combination with means for laterally moving one of said movable sides to effect a tight joint, and means for applying pressure to the other of said movable sides whereby to compress the ingot in the mold, substantially as described.

3. In an ingot-casting machine, a vertically disposed mold substantially rectangular in cross-section and having a removable 105 bottom closure and further having two of its adjacent sides movable, in combination with means for laterally moving one of said movable sides to effect a tight joint, and means for applying pressure to the other of said 110 movable sides whereby to compress the ingot in the mold, substantially as described.

4. In an ingot-casting machine, a vertically disposed mold substantially rectangular in cross-section and having a removable 115 bottom closure adapted to permit the discharge of the ingot through the bottom of the mold, and further having two of its adjacent sides movable, in combination with means for elastically holding one of said movable sides in operative position during the molding of the ingot, and means for applying pressure to the other of said movable sides whereby to compress the ingot in the mold, 120 substantially as described.

5. In an ingot-casting machine, the combination with a frame, of a vertically disposed mold mounted in one end of said frame and having a laterally movable inner side member, a plunger cylinder and plunger 130

mounted in the other end of said frame, a cross-head slidably mounted in said frame between and in contact with the outer end of said plunger and the outer face of said movable mold-member, connections between said cross - head and movable mold - member adapted to effect the retraction of the latter, and means for retracting said cross-head after compression of the ingot has been effected, substantially as described.

6. In an ingot-casting machine, the combination with a frame, of a vertically disposed mold mounted in one end of said frame and having adjacent laterally movable side members, a plunger cylinder and plunger mounted in the other end of said frame, a cross-head slidably mounted in said frame between and in contact with the outer end of said plunger and the outer face of one of said movable mold-members and loosely connected to the latter, means for holding said other laterally movable mold-member in operative position during the molding of the ingot, and means for simultaneously releasing the latter and retracting said cross-head after compression of the ingot has been effected, substantially as described.

7. In an ingot-casting machine, the combination with a frame, of a vertically disposed mold mounted in one end of said frame and having adjacent laterally movable side members, a plunger cylinder and plunger

mounted in the other end of said frame, a cross-head slidably mounted in said frame between and in contact with the outer end of said plunger and the outer face of one of said movable mold-members and loosely connected to the latter, wedges and means for actuating them into and out of engagement with said other laterally movable mold-member, said wedges on their retracting movement serving also to effect the retraction of said cross-head after compression of the ingot has been effected, substantially as described.

8. An ingot-mold of substantially rectangular cross-section having two of its adjacent sides laterally movable, in combination with means for supporting said mold in an upright position, and a removable bottom closure permitting the discharge of the ingot by gravity through the lower end of the mold, substantially as described.

9. An ingot-mold of substantially rectangular cross-section having two of its adjacent sides laterally movable, in combination with means for supporting said mold in an upright position, and a hinged bottom plate permitting the discharge of the ingot by gravity through the lower end of the mold, substantially as described.

LESLIE E. HOWARD.
